Primary Examiner — Kelley A Donnelly*(74) Attorney, Agent, or Firm* — Brooks Kushman P.C.;
Lora Graentzdoerfler(57) **CLAIM**

The ornamental design for a shower door display, as shown and described.

DESCRIPTION

FIG. 1 is a perspective view of a shower door display according to an embodiment;

FIG. 2 is a front side elevation view of the shower door display of FIG. 1; and,

FIG. 3 is a right side elevation view of the shower door display of FIG. 1.

The broken lines are for illustrative purposes only and form no part of the claimed design.
